Inventor

Peter Christensen

By his Attorney

Michael Kilgore

UNITED STATES PATENT OFFICE.

PETER CHRISTENSEN, OF ST. LOUIS PARK, MINNESOTA.

REGISTER-GRILLE ANCHORING DEVICE.

Application filed October 12, 1921. Serial No. 507,339.

To all whom it may concern:

Be it known that I, PETER CHRISTENSEN, a citizen of the United States, residing at St. Louis Park, in the county of Hennepin and 5 State of Minnesota, have invented certain new and useful Improvements in Register-Grille Anchoring Devices; and I do hereby declare the following to be a full, clear, and exact description of the invention, such as 10 will enable others skilled in the art to which it appertains to make and use the same.

My invention has for its object to provide improved means for rigidly and adjustably anchoring register grilles to air conduit terminals in hot air heating systems.

Generally stated, the invention consists of the novel construction and combinations of parts hereinafter described and defined in the claims.

20 In the accompanying drawings, which illustrate the invention, like characters indicate like parts throughout the several views.

Referring to the drawings:

Fig. 1 is a front elevation with some parts 25 broken away and some parts sectioned, showing a register grille anchored to an air conduit terminal with my improved anchoring device;

Fig. 2 is a section on the line 2—2 of Fig. 30 1, some parts being shown in full;

Fig. 3 is a horizontal section taken approximately on the line 3—3 of Fig. 1;

Fig. 4 is a fragmentary view taken approximately on the same line as Fig. 3, showing less of the device than Fig. 3 but on a 35 larger scale; and

Fig. 5 is a perspective view showing one of the anchoring bars.

The wall 6 illustrated is a masonry wall 40 but might be of other construction. The numeral 7 indicates the air conduit terminal, which is imbedded in or otherwise anchored in the wall 6 and, at its inner end, is formed with an inturned flange 8.

45 The grille 9, as shown, is a cast structure that might be of any other suitable form. Near each side, the grille is formed with screw passages through which screws 10 are freely passed. The threaded ends of these 50 screws 10 are engageable with internally threaded lugs 11 formed on anchoring bars 12. These anchoring bars 12, as preferably constructed, are formed with reduced edges 13 that are adapted to engage the inner faces 55 of the flanges 8 of the conduit terminal 7. When said screws are tightened, not only

will the anchoring bars be drawn tightly against the terminal flanges 8 but the projecting marginal portions of the grille will be tightly drawn against the inner face of 60 the wall or against the plaster 14 when said wall is a plastered wall.

Thus, the grille may be very quickly and securely clamped in position and, moreover, it is capable of considerable vertical, lateral 65 and angular adjustments in the plane of the wall and, hence, may be set in a true position irrespective of whether or not the conduit terminal is accurately set in the wall and irrespective of whether or not the terminal flanges 8 are flush with the finished 70 surface of the plaster or are considerably inward thereof.

It is important to note that the screws 10 engage the intermediate portions of the 75 anchoring bars, so that the latter are capable of oscillatory or angular movements in respect to the marginal edges of the grille. This permits the grille to be set in a true vertical position, even when the conduit ter- 80 minal is not in true vertical position.

In actual practice, these anchoring devices have been found not only to be efficient for the purposes had in view, but it has been found that a great deal of time and labor 85 may be saved by the use thereof, and that, as already stated, the grille may always be quickly and accurately set.

What I claim is:

1. The combination with an air conduit 90 terminal applicable to a wall and having flanges adjacent to one of the faces of the wall, of a register grille outward of said flanges, anchoring bars engaging the inner faces of said flanges, and having lugs and 95 adjustable devices between said lugs and register grille for clamping the anchoring bars onto said flanges and the register grille against the wall, said adjustable devices permitting longitudinal angular and pivotal 100 movements of the anchoring bars in respect to the register grille.

2. The combination with an air conduit 105 terminal applicable to a wall and having flanges adjacent to one of the faces of the wall, of a register grille outward of said flanges, anchoring bars having reduced edges engaging the inner faces of said flanges, each of said bars having at its intermediate portion an offset lug spaced apart 110 from said flanges, and adjustable devices between said lugs and the register grille for

clamping the anchoring bars onto the flanges and the register grille against said face of the wall.

3. The combination with an air conduit terminal applicable to a wall and having flanges adjacent to one of the faces of the wall, of a register grille outward of said flanges, anchoring bars engaging the inner faces of said flanges and extending substantially the full length thereof, each of said bars having at its intermediate portion an offset lug spaced apart from said flanges, and adjustable devices between said lugs and grille for clamping the anchoring bars onto said flanges and the register grille against the wall.

4. The combination with an air conduit

terminal applicable to a wall and having flanges in rectangular arrangement adjacent to one of the faces of the wall, of a register grille outward of said flanges, a pair of anchoring bars engaging the inner faces of opposite flanges on said terminal, extending substantially the full length thereof and overlapping the other of said flanges, each of said bars having at its intermediate portion an offset lug spaced apart from said flanges, and adjustable devices between said lugs and grille for clamping the anchoring bars onto the flanges and the register grille against the wall.

In testimony whereof I affix my signature.

PETER CHRISTENSEN.
